CONTROL SYSTEM

Harold B. LaRoque, Scotia, N. Y., assignor to
General Electric Company, a corporation of
New York

Application July 15, 1933, Serial No. 630,569

2 Claims. (CL 177—346)

My invention relates to control systems for electric circuits, more particularly to control systems for electric lamps, and has for its object simple and reliable means giving flexibility of control.

This application is a continuation in part of a copending application of Harold B. LaRoque and Frank R. Elder, Ser. No. 556,702, filed August 12, 1931, now Patent No. 2,016,148, dated October 1, 1935.

My invention has special use in the control of electric circuits containing incandescent lamps. It is particularly useful in the control of decorative lighting installations such as for show windows, floodlighting, electric signs, etc. In connection with the control of the electric lamps an object of the invention is an automatic mobile color-lighting system operating to give a predetermined sequence of color control with blending of colors.

My invention also comprehends the control of a plurality of banks of lights, preferably of different colors, in some predetermined relation as to degree of illumination, together with means whereby this relation may be continuously varied.

In carrying out my invention I provide a plurality of devices for controlling the degree of illumination of the lamps and a plurality of groups of lamps, preferably of different colors together with selective switching means for connecting the control means as desired to the various groups of lamps. The control means are operated at different speeds, some giving a relatively slow rise and fall of illumination, while the others, being driven at higher speed, giving a comparatively fast rise and fall of illumination. With this control one group of lamps may be passing slowly through a cycle of darkness to full brilliancy and then back to darkness, while at the same time another group or groups of lamps under the control of the fast controllers may be blended with the slow group.

For a complete understanding of my invention reference should be had to the accompanying drawing, Fig. 1 of which shows in diagrammatic form a system of illumination control embodying my invention, Fig. 2 is a diagrammatic view of a typical control device, while Fig. 3 is a diagrammatic view of the discharge devices and reactances for further controlling the lamp.

Referring to the drawing, I have shown my invention in one form as applied to the control of a plurality of groups or banks of lamps 10 to 17 inclusive of various colors as indicated on the drawing, these groups of lamps being pref-

erably arranged to illuminate a common area or adjacent areas so that their lights may be blended or contrasted. It will be understood that the rectangular figures to which the reference numerals are applied each include, as well as the lamps, the electron discharge and reactance control devices as shown in Fig. 3, to be hereinafter described in detail.

The various groups of lamps are controlled by control devices indicated by rectangular figures 18 to 21 inclusive. Each control device includes a rotatable inductance coil 22 (Fig. 2) with co-operating circuits to give a suitable phase shifting control for the electron discharge devices when the coil 22 is rotated. This control means will hereinafter be described in detail in connection with Fig. 2.

The coils 22 of the phase controllers 18 to 21 inclusive are driven by a common driving motor 23, preferably of a constant speed type, through a common drive shaft 24 and suitable gearing. This gearing has different ratios, the control devices 18 and 19 being driven at the same speed, which, however, is relatively slow as compared with the speed of the control devices 20 and 21.

Associated with the controllers 18 to 21 inclusive are respectively selector switches 25 to 28 inclusive, as indicated in the drawing. Each of these switches comprises a rotatably mounted contact arm 29 which cooperates with spaced contacts 30. The contact arms of the four switches are mounted on a common drive shaft 31. They may be turned step by step in a clockwise direction from one contact to another by means of a suitable mechanism comprising a ratchet wheel 32 mounted on the shaft 31 and a pawl 33 cooperating therewith. This pawl is mounted on a plunger armature 34 provided with an operating coil 35. The circuit of the coil 34 is controlled by means of a switch 36 which is normally opened but closed once each revolution of a disk 37 carrying a projecting pin 38 arranged to strike one of the contacts of the switch and bring it into engagement with the other. This closes the circuit of the coil 35 which thereupon picks up the plunger 34 and advances the contact arms to the next contact.

The disk 37 is driven at a suitable speed, preferably at the same speed as the fast phase controllers 20—21, and as shown the disk is mounted on the shaft of the phase controller 21.

The advancement of the contact arms effects the connection of the groups of lamps to the various control devices in accordance with a predetermined sequence. Preferably this change or

transfer in the control takes place at a predetermined period in the lighting cycle, ordinarily when the lamps are completely dark. This adjustment for the period of transfer is made by 5 relatively arranging the pin 38 with respect to the switch 36 so that the switch is closed at the desired time.

It will be observed that the stationary contacts 30 of the various selector switches have various 10 connections to the groups of lamps, and these connections may be arranged as desired to give the desired illumination, the desired colors and the desired blending of colors. The selector switch 25, for example, has its first four contacts, 15 counting from the top, electrically connected together and in turn electrically connected to the green group of lamps 10. The contacts 5 and 6 of this switch have no electrical connections and therefore are dead, while the lower four contacts 20 are electrically connected together and in turn connected through a conductor 40 to the green group of lamps 10. The selector switches 26, 27 and 28 have their stationary contacts arranged 25 differently in suitable groupings and connected to various groups of lamps, all of which will be clear from the drawing.

It will be understood that one complete revolution of the disk 37 represents a complete cycle for the fast controllers, that is, from dark to full 30 brilliancy and back again from full brilliancy to dark. Therefore the lamps connected to the fast controllers go through a complete cycle during the time that the contact arms of their respective selector switches are in engagement with any 35 particular stationary contact which is being utilized in a control circuit. This is not true, however, with respect to the slow controllers 18 and 19. These controllers are preferably driven at one-half the speed of the fast controllers although a different ratio which is also an even 40 number may be used. With the one-half speed ratio the groups of lamps connected to the slow controllers can only go through one-half of the cycle, i. e., from dark to full brilliancy or vice 45 versa, while the contact arms of their particular selector switches are in engagement with any particular stationary contact which is in use. It 50 will be observed, therefore, that while the contact arm of the selector switch 25 is cooperating with the first four contacts, the groups of lamps controlled thereby, i. e., the group 10, is carried through two complete cycles. That is, while the contact arm is in engagement with the upper stationary contact, the group of lights 10 is 55 raised to full brilliancy. The contact arm is then shifted to the second contact and the lights reduced to full darkness. When the contact arm is shifted to a third contact, the lights are raised again to full brilliancy and then darkened when 60 the contact arm is shifted to the fourth contact. It will be understood that the contact arms are snapped quickly from one contact to the other upon energization of the operating coil 35 and because of this and the time constants of the 65 reactors no appreciable dimming or flickering of the lights is observed. This applies particularly to the slow controllers 18 and 19 since the fast controllers 20 and 21 are transferred when the lights are dark. It will be observed that this 70 transfer of control when the lights are either dark or fully brilliant is dependent upon the operation of the fast and slow controllers at speeds having an even ratio to each other as disclosed.

75 The connections of the control devices in the

various combinations will be clear from the previous description, without tracing through the respective circuits for each particular controller and selector switch.

Referring to Fig. 2, while any suitable control 5 device may be used for controlling the electron discharge devices, I have shown a phase shift controller such as described and claimed in a copending application of Harold B. LaRoque and Frank R. Elder, Serial No. 556,702, filed August 10 12, 1931, assigned to the same assignee as this invention. This control device comprises a suitable resistance 41 which is connected across supply conductor 42 leading to a suitable alternating supply source. Connected in parallel relation with the resistance 41 is an inductance coil 43 and a second resistance 44, the inductance 43 and the resistance 44 being connected in series with each other. A third resistance 45 is connected between the junction point 46 of the inductance 43 and the resistance 44 and an adjustable intermediate point 47 on the resistance 41. The inductance coil 22 driven by the motor 23 is preferably provided with a rotatable iron core armature 48. This coil is in inductive relation 25 with the inductance coil 43, which preferably also has an iron core. One terminal of the inductance coil 22 is connected to a point between the inductance 43 and the resistance 44, while the other terminal 49 of the coil 22 constitutes one 30 output terminal of the controller. A conductor 50 leads to an adjustable point on the resistance 45, this conductor 50 constituting the other output terminal of the controller.

It will be observed that a voltage is induced in 35 the coil 22 by reason of its inductive relation with the coil 43, which voltage varies in magnitude from a maximum value in one direction to a maximum value in an opposite direction. This voltage when added to or subtracted from the voltage 40 drop across the resistance 45 gives a resulting voltage across the terminals 49 and 50, the phase position of which with relation to the supply 45 source 42 is dependent upon the angular position of the coil 22.

Referring to Fig. 3, it will be understood that 45 each of the rectangles of Fig. 1, referred to as lamps, includes the control devices shown in Fig. 3 in addition to a group of lamps 51 of selected color. The degree of illumination of the lamps is 50 controlled by a suitable iron core reactance device 52 having a winding connected in series with the lamps to supply conductors 53 leading a suitable alternating-current supply source which is the same as the source to which the supply conductors 42 of Fig. 2 are connected. The reactance of the 55 reactance device 52 is in turn controlled to control the lamps by means of suitable discharge devices 53 and 54, which are connected to rectify both halves of the alternating current wave supplied 60 to their output circuits from the supply conductors 53 through a transformer 55. Preferably the electron discharge devices 53 and 54 are three-element devices of the mercury-vapor type, 65 which devices act as arc rectifiers. As is well known in the art, the sealed envelope of a discharge device of this type contains a small quantity of inert gas such as mercury vapor, whereby the device becomes an arc rectifier, its arc formation being controlled by a grid.

The terminals of the secondary windings of the 70 transformer 55 are connected respectively to the anodes 56 and 57 of the discharge devices. A central point 58 of this secondary winding is con- 75

5 nected through a conductor 58 and a saturating winding 60 on the reactor 52 to the cathodes 61 and 62 of the discharge devices. The cathodes are also connected to a suitable heating trans-
5 former 63. It will be understood that the output circuit through the controlling reactance winding 60 is completed through the cathodes and anodes of the discharge devices alternately when they are in operation so as to rectify predetermined por-
10 tions of both halves of the alternating-current cycle under the control of the grids 64 and 65.

10 The grids are supplied with a control voltage from the secondary winding of a grid transformer 66 having the terminals of its secondary winding 15 connected respectively to the grids and having a mid-point of its secondary winding connected through a grid current limiting resistance 67 to the cathodes of the discharge devices. The primary winding of the grid transformer 66 is connected to the output conductors 49 and 50 of the phase-shifting control device shown in Fig. 2. One of these conductors, for example the conductor 50, is connected directly to the primary of the grid transformer 66, the other conductor 49 20 being connected selectively to the other terminal 68 of the grid transformer through one of the selector switches. As shown in Fig. 1, the output conductors 50 of the various phase-shifting control devices 18 to 21 inclusive are connected to a common conductor 70 which in turn leads to one terminal of each of the grid transformers 66 associated with the various groups of lights, while the conductors 49 of the four phase-shifting control devices lead respectively to the four contact arms 30 of the selector switches.

35 In the operation of the discharge devices, when the grid voltage applied by the particular phase-shifting controller lags behind the anode voltage 52 by a predetermined angle, which may be approximately 120°, the grids of the discharge devices become sufficiently positive to set the discharge devices in operation only during approximately the last 60° of the positive half of the voltage wave, the two discharge devices thus operating to supply a pulsating direct current only during these relatively small portions of the waves. This does not energize the lamps sufficiently to cause them to emit any visible or appreciably visible illumination and consequently 40 the lights are dark. This condition will correspond with one of the positions of maximum voltage of the coil 22 such as shown in Fig. 2. As the coil 22 is turned from that position its voltage decreases and consequently the grid voltage is 45 shifted more and more in phase with the anode voltage so that greater and greater portions of the alternating waves are rectified with correspondingly increased energization of the lamps, whereby they are gradually brought up to full brilliancy, 50 this occurring when the grid voltage is approximately in phase with the input voltage. Under these conditions the coil 22 will have a position approximately 180° from the position shown in Fig. 2. In other words it will have maximum 55 voltage induced in it in the opposite direction. As the coil 22 continues its rotation its induced voltage gradually decreases and consequently the lamps are gradually lowered from full brilliancy to darkness again to complete the cycle.

60 70 Preferably the pin 38 of Fig. 1 closes the contacts 36 so as to operate the selector switches at the time the coil 22 is in the position shown in Fig. 2, that is, when the lights are dark.

75 Any suitable type of reactance may be used to

control the lamp circuit. Preferably, however, the reactance comprises two similar windings 69 and 70 connected in parallel in the lamp circuit on a suitable iron core and oppositely wound so that their induced voltages exactly counterbalance each other while surrounding these two windings is the direct current saturating winding 60. This arrangement prevents detrimental inductive action between the winding 60 and the two windings 69 and 70. It will be understood 10 that the current in the lamp circuit is controlled by varying the saturation of the core of the reactance by means of the current through the winding 60, an increase of current in the winding 60 increasing the saturation and hence increasing the brilliancy of the lamps, and vice versa.

What I claim as new and desire to secure by Letters Patent of the United States, is:—

1. The combination in a system of control for a plurality of groups of electric lamps, of a plurality of control means for said groups mounted for continuous rotation in a predetermined direction for varying the intensities of illumination of said groups of lamps from darkness to full brilliancy and back to darkness during each revolution, a driving motor, driving connections between said motor and said control means having different speed ratios whereby said control means are driven at high and low speeds having a predetermined ratio to each other which is an even number, selective switching means for controlling the connections between said plurality of control means and said groups of lamps, electromagnetic means for moving said selective switching means from one position to the next, connections for energizing said electromagnetic means, a normally open switch in said connections for selectively energizing and de-energizing said electromagnetic means, and an operating 20 connection between said first control means and said switch for operating said switch to its closed position after a predetermined rotation of said control means to thereby energize said electromagnetic means momentarily to move said selective switching means to another position, said operating connection being arranged relative to the angular position of said high speed control means to close said switch when said control means are in positions for maximum or minimum 25 intensities of illumination of said groups of lamps. 30

2. The combination in a system of control for a plurality of groups of different colored electric lamps, of a plurality of control devices for said groups of lamps each comprising a winding 35 mounted for continuous rotation to thereby produce a voltage varying during each revolution from a maximum value in one direction through zero to a maximum value in the opposite direction and then back to the maximum value in the first direction, voltage responsive means associated with each of said groups of lamps for varying the brilliancy of said lamps from darkness to full brilliancy and back to darkness during each revolution of said winding, a selector device movable successively to a plurality of positions for simultaneously transferring the connections of said voltage responsive means from one set of control devices to another set of control devices, a solenoid having an armature connected to said selector device so as to operate said selector device from one position to the next when said solenoid is energized, connections for energizing said solenoid, a switch for said 40 45 50 55 60 65 70 75 80 85 90 95

solenoid in said connections, a driving motor, driving connections between said motor and said control devices having different ratios whereby said control devices are driven at predetermined high and low speeds having a predetermined ratio to each other which is an even number, an operating member connected to be driven by one of said fast control devices for momentarily closing said switch once each revolution of said fast

control device, said operating member being so angularly related to the winding of said fast control device that it closes said switch when the voltage produced by said winding is a maximum value whereby said groups of lamps are either fully dark or fully brilliant when said selector device is operated from one position to the next. 5

HAROLD B. LAROQUE.
